CLAIM

The ornamental design for a wearable pet monitor, as shown and described.

DESCRIPTION

FIG. 1 is a top front left perspective view of a wearable pet monitor, showing our new design in condition of use.

FIG. 2 is a top front left perspective view of the wearable pet monitor of FIG. 1, shown in an alternate configuration.

FIG. 3 is a front view thereof.

FIG. 4 is a rear view thereof.

FIG. 5 is a right-side view thereof.

FIG. 6 is a left-side view thereof.

FIG. 7 is a top plan view thereof.

FIG. 8 is a bottom plan view thereof.

FIG. 9 is an exploded top front left perspective view of the wearable pet monitor of FIG. 2; and,

FIG. 10 is an exploded bottom front right perspective view of the wearable pet monitor of FIG. 2.

The broken lines illustrate portions of the wearable pet monitor that form no part of the claimed design.
